The ornamental design for a religious toy figurine, as shown and described.

DESCRIPTION

FIG. 1 is a front elevational view of the religious toy figurine of the present invention;

FIG. 2 is a left side elevational view of the religious toy figurine of FIG. 1;

FIG. 3 is a rear elevational view of the religious toy figurine of FIG. 1;

FIG. 4 is a right side elevational view of the religious toy figurine of FIG. 1;

FIG. 5 is a top plan view of the religious toy figurine of FIG. 1; and

FIG. 6 is a bottom plan view of the religious toy figurine of FIG. 1.

FIG. 1.
The broken lines showing of a doll in FIGS. 1-6 are for illustrative purposes only and form no part of the claimed design.
